United States Patent Office

Des. 196,823
Patented Nov. 5, 1963

196,823
GUIDED MISSILE

Alvar G. Carlton and John A. Tiedeman, Silver Spring,
James H. Walker, Fulton, and Guy Worsley, Sumner,
Md., assignors to the United States of America as rep-
resented by the Secretary of the Navy

Filed Oct. 2, 1962, Ser. No. 71,979

Term of patent 14 years

(Cl. D71—1)

FIG. 1 is a perspective view of a guided missile showing our new design;

FIG. 2 is a bottom plan view of the missile;

FIG. 3 is a top plan view of the missile;

FIG. 4 is a side elevation thereof;

FIG. 5 is a front elevation of the missile; and

FIG. 6 is a rear elevation thereof.

We claim:

The ornamental design for a guided missile, as shown.
